UNITED STATES PATENT OFFICE.

JOHN C. DODS, OF PHILADELPHIA, ASSIGNOR, BY DIRECT AND MESNE ASSIGNMENTS, TO HENRY W. OLIVER, JR., AND JAMES P. WITHEROW, OF PITTSBURG, PENNSYLVANIA.

CONVERTER.

SPECIFICATION forming part of Letters Patent No. 328,841, dated October 20, 1885.

Application filed June 30, 1884. Serial No. 136,429. (No model.)

To all whom it may concern:

Be it known that I, JOHN C. DODS, a subject of the Queen of Great Britain and Ireland, residing in Philadelphia, Pennsylvania, 5 have invented certain Improvements in Converters, of which the following is a specification.

My invention relates to that class of Bessemer converters in which horizontal tuyeres 10 are employed to permit of the use of a low-pressure blast, the object of my invention being to so construct the converter as to facilitate the lining and repairing of the same without delay or great expense, while permitting the 15 introduction and removal of the metal through the usual mouth of the converter.

In the accompanying drawings, Figure 1 is a vertical section of a Bessemer converter made according to my invention, and Fig. 2 is 20 a sectional plan on the line 1 2, Fig. 1.

My converter is of the class termed "trunnion-mounted converters," the trunnions B B' being adapted to suitable bearings, which are not shown in the drawings, as they form no 25 part of my invention. The use of the trunnions permits the metal to be introduced and discharged through the mouth, as usual, permits the blast to be stopped at any time, and also permits the main body of the converter to 30 be turned upside down for repairs, as herein-after described.

The body of the converter is composed of two main parts—namely, the upper portion, A, which is mounted in the ring or belt composed of two segments, h h', and forming parts 35 of the trunnions, while the lower portion of the converter, A', is made separable from the upper part on the line a, Fig. 1. This lower portion carries the blast-chamber E, of any ordinary construction, and insertable side tuyeres, m, which extend at intervals from the chamber E into the interior of the converter, and this removable portion A' is of a depth sufficient to contain the entire charge.

45 The trunnion B is hollow, as usual, for the reception of the end of the blast-pipe b, the interior of the trunnion communicating through a pipe, d, and branch e with the blast-chamber E.

50 Each portion A and A' of the body of the

converter has a lining, z, of refractory material, and the metal casing of the lower portion, A', of the converter is provided with a flange, i', adapted to be secured to a flange, i, on the belt h h', which carries the trunnions of the 55 upper portion.

That portion of the lining which contains the charge of metal is worn and otherwise deteriorated more rapidly than any other part; but, since in my converter the removable portion A' contains the charge, this portion can be replaced by another, or it can be quickly repaired and applied to the portion A, which is mounted on its trunnions.

For each upper portion of the converter I 65 propose to furnish two or more extra lower or removable portions, which shall always be ready for application to the upper portion, the linings of these extra parts being readily prepared for use, as they will contain a sufficient 70 supply of ignited charcoal or coke to dry and harden the lining and to properly heat it, so that the converter will be ready for immediate use as soon as the extra lower portion is in place. On the other hand, when the upper 75 portion, A, of the converter requires repairing, all that is necessary, after taking out the portion A', is to turn the part A on its trunnions upside down, or partially so, so that it may be rammed up with ganister and repaired 80 by patching. This is a great advantage over the fixed converter, as that is lined with fire-brick and cannot be kept in repair, but is used until worn out and is then relined.

A further advantage over the fixed converter 85 is that whereas in the latter the blowing of the air or gas through the tuyeres has to be continued until the metal is entirely removed, in order to prevent it from backing into the tuyere-holes, in the tilting converter, on the 90 other hand, there is no such necessity for keeping up the blast after treatment, as the molten metal is carried away from the tuyeres by simply turning the converter on its trunnions.

The object of employing the horizontal 95 tuyeres is that it permits the use of low pressure, which, as is well known, eliminates the silicon more completely than where high pressure is used, and reduces the cost of the blowing-engine.

I am aware that converters have heretofore been provided with removable bottoms of a size to contain the charge, and that horizontal tuyeres also are not new in converters; but, so 5 far as I am aware, it is new to provide a trunnion-mounted converter with a removable bottom provided with tuyeres extending through the side at intervals entirely around the converter, so as to treat the charge uniformly on 10 all sides, of a size sufficient to contain the charge, and containing horizontal tuyeres.

I claim as my invention—

1. A sectional converter having supporting-trunnions on its upper section, on which the 15 converter may be tipped, and a removable lower section for containing the charge, provided with tuyeres extending through its sides

at intervals entirely around the converter, substantially as and for the purposes described.

2. A sectional converter having supporting-trunnions on its upper section, on which the converter may be tipped, and a removable lower section for containing the charge, provided with a circular blast-chamber and side tuyeres, substantially as and for the purposes 20 25 described.

In testimony whereof I have signed my name to this specification in the presence of two subscribing witnesses.

JOHN C. DODS.
